UNITED STATES PATENT OFFICE

2,004,004

WEATHERPROOF ARMORED CABLE

Homer G. Knoderer, Fairfield, Conn., assignor to
 General Electric Company, a corporation of
 New York

Application April 1, 1933, Serial No. 663,974
 Renewed February 8, 1935

4 Claims. (Cl. 173—266)

My invention relates to an improved weather-proof armored cable.

In connecting a house wiring system to the power supply lines, it has been a common practice to use rigid conduit extending up the side of the house and to pass the conductors through it. The use of rigid conduit produces an expensive installation and in addition such an installation has proven to be one from which electric current may readily be taken in an unauthorized manner.

The object of my invention is to provide an improved weatherproof armored cable of relatively low cost of manufacture, easy to install, resistant to the effects of atmospheric conditions and practically theftproof.

What I consider to be novel and my invention will be better understood by reference to the following specification and appended claims, when considered in connection with the accompanying drawing.

In the accompanying drawing, Fig. 1 is a plan view of my electric cable with the layers of insulation cut away to expose the layers beneath and Fig. 2 is a sectional view of the cable.

Referring to the drawing, two conductors 10 and 11 consist of strands 12 and 13 of relatively large diameter wound together spirally to form a flexible core. The conductors 10, 11 are provided with the usual layer of rubber insulation 14, 15 covered by a cotton braid 16 and 17. The cotton braids 16 and 17 may be impregnated with colored wax to distinguish them; one may be impregnated with a red wax and the other with a black wax. Over the combined conductors 10 and 11 with their insulation is wound a paper strip 18. This paper strip is used to secure the conductors together and provide a smooth continuous surface over them. It may be omitted in some instances if found desirable. The conductors 10 and 11 as shown are laid longitudinally side by side but they may be wound together spirally if desired to increase the flexibility of the cable. A bare conductor 19 is wound spirally around the conductors 10 and 11. It consists of a number of strands 20 of relatively small diameter. The strands 20 are evenly distributed about the combined surface of the conductors 10 and 11 and are sufficiently great in number to provide a practically continuous surface. The diameter of strands 20 is such, preferably, that the combined cross section of all of the strands forming the conductor 19 is equal to the cross section of each of the conductors 10 and 11.

However, it is not necessary that the cross section of conductor 19 be exactly equal to the cross section of conductors 10 and 11. It may be somewhat less as the greater surface of conductor 19 provides a relatively large area for the dissipation of heat and with the same current density in the conductor 19 as is in conductors 10 and 11, the temperature rise due to the flow of current will be less. Therefore, for the same temperature rise the cross section of the conductor 19 may be somewhat smaller than the cross section of each of the conductors 10 and 11. About conductor 19 an armor 21 is wound consisting of a half round strip of metal wound spirally with the turns in spaced relation to each other. In place of armor 21 an interlocked armor may be used. However, this half round armor with the turns spaced apart provides somewhat greater flexibility with sufficient mechanical protection for the conductors and is also of lighter weight as compared with an interlocked armor. Armor 21 is wound in the opposite direction to the strands 20 of conductor 19. This provides a greater flexibility. Also, it is easier to remove than if the two were wound in the same direction. Over the armor 21 a layer 22 of rubber filled tape is wound spirally. Over the layer 22 a layer 23 of waterproofing compound, such as an asphaltic compound, is applied. The asphaltic compound serves to provide the primary source of weatherproofing for the cable. The layer 22 of rubber filled tape serves as a separator between the layer 23 of asphaltic compound and the armor 21 and bare conductor 19. In place of the rubber filled tape 22, a covering of fibrous material may be used to serve as a separator. The rubber filled tape however provides an additional measure of weatherproofing for the cable. Over the layer of asphaltic compound a layer of rubber filled tape 24 is wound spirally. This layer 24 serves also as a separator between the asphaltic compound and any additional covering applied to the cable.

An overall cotton braid 25 is provided which is of relatively heavy material and is impregnated with a flameproof saturant such as stearin pitch.

To connect the cable to the power conductors or to a service switch in a house, the ends of the conductors are prepared by first cutting and removing the braid 25 and the two tapes 22 and 24. This is a very simple operation. Armor 21 is then removed by unwinding it as far back from the end as desired and cutting the strip with a pair of pliers or other tool. Strands 20 are then unwound back to where the armor has been.

5 moved and bunched by winding the strands 20 together spirally. Paper strip 18 is unwound from around the two conductors and the insulation from conductors 10 and 11 is removed by scraping it from the end of the conductors in the usual manner. The conductors 10 and 11 may then be connected to the ungrounded sides of the line and conductor 19 to the grounded side.

10 It is to be understood that the invention is not limited to a cable consisting of two insulated conductors and one bare conductor but is equally applicable to any cable having one or more insulated conductors surrounded by a bare conductor. This cable may also be used to bring a connection from a pole on which a transformer is supported to the house as well as to make a connection to the separate conductors as usually brought from the pole to the side of the house. This is made possible by the relatively light 20 weight of the cable. Such an arrangement makes the cable weatherproof from its point of connection to the supply at the pole to the point of its entrance into the house.

25 It is to be noted that in my improved cable the weatherproofing compound is applied only outside of the armor to facilitate the stripping of the conductors. Also, a separator is provided between the weatherproofing compound and the armor in order to prevent the weatherproofing compound adhering to the armor and interfering with the grounding of the armor. Additional protection of the conductors against use by unauthorized persons is provided by winding an uninsulated conductor around one or more insulated conductors and so completely surrounding the conductor or conductors that it is practically impossible to make contact with the inner conductors without contacting with the bare conductors. This bare conductor is also one of 35 the supply conductors and is secured in place by an armor which in addition provides mechanical protection for the conductors.

40 From the foregoing it will be seen that an improved weatherproof armored cable is provided which is relatively easy to install, which is thoroughly protected from atmospheric conditions, mechanically protected to provide the necessary strength, and in addition is provided with means to prevent the theft of electric current therefrom. Also, the arrangement of the bare conductor and the half round armor strip reduces

5 the size of the cable as well as the amount of material necessary, consequently reducing the cost of manufacture of the cable.

What I claim as new and desire to secure by Letters Patent of the United States, is,—

5

1. In an electric cable, an electric conductor, insulating material surrounding said conductor, a second conductor consisting of strands spirally wound about said conductor and insulation, a metallic armor wound around and in contact 10 with said second conductor, a tape of fibrous material covering said armor, a weatherproofing compound covering said tape, and an overall braid of fibrous material impregnated with a flameproof material.

15

2. In an electric cable, a conductor, insulation surrounding said conductor, a second conductor consisting of strands wound around said first conductor and insulation, an armor surrounding said second conductor and in contact therewith, 20 an overlapping wrap of rubber filled fabric tape covering said armor, a layer of asphaltic compound over said tape, a second wrap of rubber filled tape over said layer of asphaltic compound and an overall braid of fibrous material impregnated with a flameproofing compound.

25

3. In an electric cable, a plurality of conductors, insulation surrounding said conductors, a conductor consisting of strands wound around said conductors and insulation, an armor surrounding said last mentioned conductor and in contact therewith, an overlapping wrap of rubber filled fabric tape covering said armor, a layer of asphaltic compound over said tape, a second wrap of rubber filled tape over said layer of asphaltic compound, and an overall braid of fibrous material impregnated with a flameproofing compound.

30

4. In an electric cable, a plurality of conductors, insulation surrounding each conductor, a 40 paper strip wound spirally over said conductors and insulation, a conductor consisting of strands wound over said paper strip, an armor surrounding said last mentioned conductor and in contact therewith, a rubber filled fabric tape covering said armor, a layer of asphaltic compound over said tape, a second wrap of rubber filled tape over said layer of asphaltic compound, and an overall braid of fibrous material impregnated with a flameproofing compound.
